BEVERAGE SET

Filed July 25, 1931

UNITED STATES PATENT OFFICE

HARRY KORN, OF BROOKLYN, NEW YORK, ASSIGNOR TO ARTCRAFT IRON WORKS, INC.,
A CORPORATION OF NEW YORK

BEVERAGE SET

Application filed July 25, 1931. Serial No. 553,088.

The present invention relates to beverage sets and is more particularly directed toward a portable beverage set adapted to support a plurality of tumblers and a water pitcher.

5 The invention contemplates the provision of a stand suitable for carrying the tumblers and water pitcher and provided with suitable legs to support it above the floor or table and with suitable handle for carrying it.

10 The beverage set may also be provided with a receptacle to receive an ice tub so that a supply of ice may be convenient for use.

15 The present form of beverage stand is designed to employ the usual flat square tile as a table top to support the pitcher. This tile is carried in a suitable frame and the tumbler supporting devices are secured to the frame so as to carry the tumblers in a convenient accessible position.

20 The accompanying drawings show, for purposes of illustrating the present invention, two of the many forms in which it may be embodied, it being understood that the forms shown are illustrative of the invention rather than limiting the same. In these drawings:

Fig. 1 is a perspective view of one form of beverage stand;

25 Fig. 2 is a fragmentary top plan view of the upper part of the stand;

Fig. 3 is a section on the line 3—3 of Fig. 2; and

Fig. 4 is a perspective view of a modified form of construction.

30 In the drawings the tile is indicated at 10. This tile is preferably the eight inch square tile commonly employed as ornamental wall tile or for use in tile-top tables. It is received within a frame 11 consisting of a piece of angle iron bent to a square shape and welded together at some point, such as indicated at 12. Various forms of tumbler supporting means may be provided but the simplest form consists of a bent strap 13 whose ends 14, 14 are welded or otherwise secured to the corners of the frame 10. This strap is formed into a number of loops 15 and is preferably welded or otherwise secured to the frame member 11 as indicated at 16. Where the usual eight inch square tile

is employed, it is possible to place three such tumbler supporting loops along two opposite sides of the tile as indicated in Figs. 1 and 4, so that the beverage set will accommodate six tumblers which hang down as indicated in Fig. 1. Larger or smaller tile or different shaped tile will admit of supporting more or less tumblers.

55 When the beverage set is to be supported from the floor, the stand is made up in the form of long legs 17 bent to some suitable ornamental shape and preferably welded on their upper ends 18 to the frame. These legs converge inwardly and, as shown in Fig. 1, may be secured to ring 19 of such size as to conveniently support an ice tub 20.

60 A convenient form of handle may be made by bending a strip of metal to an inverted U-shape, as indicated in Fig. 1. Here the handle 21 is provided with lower bent ends 22 passing underneath the frame 11 and welded to it. The handle 21 may, if desired, be provided with a ring 23 adapted to encircle the water pitcher as shown.

65 The form shown in Fig. 4 is indicated for 75 table use, and here the legs 30 are shorter being merely sufficiently long to hold the tumblers off the support on which the legs 30 rest. Instead of providing a handle such as shown in Fig. 1, the handle here takes the 80 form of two bent straps 32 welded to the opposite sides of the frame member 10.

75 It is obvious that the invention may be embodied in many forms and constructions, and I wish it to be understood that the particular forms shown are but two of the many forms. Various modifications and changes being possible, I do not otherwise limit myself in any way with respect thereto.

85 80 What is claimed is:

90 95 1. A beverage stand having a square table top composed of a frame and an enclosed tile, supporting legs for the frame, a plurality of tumbler supporting rings secured to two opposite edges of the frame, and a handle secured to the other edges of the frame, the handle being in the form of an inverted U-shaped loop adapted to accommodate a water pitcher and carrying a horizontal ring to encircle such pitcher.

2. A beverage stand comprising a square frame made of angle iron, a square tile secured in the frame, a plurality of legs extending downwardly from the frame, and a plurality of tumbler supporting rings along the edges of the frame, the rings being formed by loops of a metal strap welded to the frame.
3. A beverage stand comprising a square frame made of angle iron, a square tile secured in the frame, a plurality of legs extending downwardly from the frame, a plurality of tumbler supporting rings along the edges of the frame, the rings being formed by loops of a metal strap welded to the frame, and an inverted U-shaped handle above the table, the ends of the handle being welded to the frame.
4. A beverage stand comprising a square frame made of angle iron, a square tile secured in the frame, a plurality of legs extending downwardly from the frame the legs converging toward one another, a ring to which the legs are secured, and a plurality of tumbler supporting rings along the edges of the frame, the rings being formed by loops of a metal strap welded to the frame.
5. A beverage stand comprising a rectangular frame formed of angle iron bent to shape and having its ends welded together, a tile secured in the frame, a plurality of tumbler supporting rings formed by straps whose ends are welded to the corners of the frame, and a plurality of downwardly extending legs welded to the frame.
6. A beverage stand comprising a rectangular frame formed of angle iron bent to shape and having its ends welded together, a tile secured in the frame, a plurality of tumbler supporting rings formed by straps whose ends are welded to the corners of the frame, a plurality of downwardly extending legs welded to the frame, and a pitcher retainer and handle in the form of a U-shaped strap whose ends are welded to the frame, the handle extending upwardly and carrying a horizontal ring to encircle the pitcher.

HARRY KORN.
